UNITED STATES PATENT OFFICE.

ELIJAH R. McCREARY, OF FRANKLINTON, LOUISIANA.

PROPELLING MECHANISM FOR VESSELS.

1,236,191.

Specification of Letters Patent.

Patented Aug. 7, 1917.

Application filed September 25, 1916. Serial No. 122,116.

To all whom it may concern:

Be it known that I, ELIJAH R. McCREARY, a citizen of the United States, residing at Franklinton, in the parish of Washington 5 and State of Louisiana, have invented certain new and useful Improvements in Propelling Mechanisms for Vessels; and I do declare the following to be a full, clear, and exact description of the invention, such as 10 will enable others skilled in the art to which it appertains to make and use the same.

My invention has for its object to provide simple yet highly efficient and durable means for easily propelling numerous kinds 15 of boats, provision being made whereby the propelling means is provided with an unusually large area for engagement with the water.

With the foregoing general object in view, 20 the invention resides in certain novel features of construction and in unique combinations of parts to be hereinafter fully described and claimed, the descriptive matter being supplemented by the accompanying 25 drawings which constitute a part of this application and in which:

Figure 1 is substantially a central vertical longitudinal section of a boat equipped with the improved propelling means;

Fig. 2 is a bottom plan view thereof;

Figs. 3 and 4 are vertical transverse sections on the planes of the lines 3-3 and 4-4 of Fig. 1 respectively;

Fig. 5 is an enlarged horizontal section on the plane of the line 5-5 of Fig. 4;

Fig. 6 is a detail vertical section on the plane of the line 6-6 of Fig. 4;

Fig. 7 is a detail elevation showing a modified form of construction.

Throughout the several views the numeral 1 designates the hull of a boat whose bottom 1 is provided with a longitudinally extending well 2 opening through the bottom of the hull, the floor 3 of said hull being preferably 45 though not necessarily below the top of the well 2 as depicted in Fig. 3.

A pair of shafts 4 extend across the ends of the well 2 and carry peripherally grooved wheels 5 around which an endless belt 6 50 passes, said belt being preferably in the form of a wire cable as shown. Any desired means may be provided for rotating one or both of the shafts 4 to propel the lower reach of a cable 6 rearwardly, but for 55 illustrative purposes one of said shafts is shown as equipped with a gear 7 by means

of which it may be connected with another gear or gears driven from the engine not shown.

Pairs of blocks 8 are clamped in contact 60 with opposite sides of the cable 6 at suitably spaced intervals by means of bolts 9, said blocks having transverse grooves 10 in their inner faces to receive the cable as shown in Fig. 6. The grooves 10 preferably converge 65 from the inner toward the outer edges of the blocks so as to readily receive the cable without unnecessarily angling the latter. The blocks 8 are provided with integral vertical flanges 11 to which laterally extending 70 blades or paddles 12 are secured by bolts or the like 13, the outer ends of said blades or paddles being disposed adjacent the sides of the well 2.

The outer ends of the blades or paddles 75 12 are provided with ears 14 riveted or otherwise secured thereto and the shanks of T-shaped guide members 15 are threaded in said ears as shown clearly in Fig. 4, the heads of said members being received between inner and outer angle metal tracks 16 and 17 which coöperate in forming a continuous hollow guideway for said heads. The head of each member 15 is provided on its ends with rollers 18 while the shanks thereof 85 are similarly equipped with rollers 19 so as to reduce friction to a minimum.

By connecting the paddles 12 with the cable 6 as shown and described they may be quickly detached whenever necessary or may 90 be adjusted on said cable to permit additional blades to be applied, and by mounting the outer ends of said blades or paddles in the manner illustrated, they will be effectively held in horizontal position and 95 will thus operate more perfectly than if the tracks or guideways were eliminated. These two features therefore are deemed the most important of the invention.

In Fig. 7 a slightly different form of construction is shown in which a wheel 5^a is shown mounted on a shaft 4^a and having a plurality of peripheral grooves, a number of cables 6^a being passed around said wheel and received in the grooves thereof. Blocks 8^a 105 identical with those illustrated at 8 contact with the outer sides of the outermost cables at suitably spaced intervals and other blocks 8^b are interposed between the numerous cables and will be provided with grooves 110 similar to those shown at 10, bolts 9^a being provided for clamping the numerous blocks

on the cables. Paddles 12^a are secured to the flanges 11^a of the blocks 8^a and since the plurality of cables 6^a will prevent tilting of said paddles, the supporting means above 5 described for the ends thereof may be eliminated. This type of the invention is particularly adaptable for use on speed boats since no friction prevails to retard the movement of the propelling means.

10 Regardless of the form of propelling means used, the hull 1 will be provided with two rudders 20 so disposed as to be on opposite sides of the current of water thrown rearwardly by the paddles 12 or 12^a. By 15 this arrangement the resistance offered by the rudders is reduced to a minimum.

From the foregoing, taken in connection with the accompanying drawings, it will be seen that although the invention is rather 20 simple and inexpensive, it will be efficient and durable. For these reasons, the structures shown and described constitute the preferred embodiments of the improved propelling means, but it is to be understood 25 that within the scope of the invention as claimed numerous changes may be made without sacrificing the principal advantages.

I claim:

1. The combination with a boat having 30 a longitudinally extending well opening through its bottom; of a pair of shafts extending transversely across the ends of said well, peripherally grooved wheels on said shafts, an endless cable trained around said 35 wheels, blocks on opposite sides of said cable at predetermined points and having transverse grooves in their inner faces receiving said cable, said grooves converging from the inner to the outer edges of the blocks, bolts 40 passing through said blocks above and below the grooves thereof for holding the former in engagement and clamping them

in binding contact with the cable, vertical flanges formed integrally with and projecting laterally from the outer faces of said 45 blocks, and paddles secured to said flanges and projecting laterally therefrom.

2. The combination with a boat having a longitudinally extending well opening through its bottom; of front and rear shafts 50 extending transversely across said well and each having a peripherally grooved wheel, an endless cable trained around said wheels, a plurality of oppositely extending paddles carried by said cable, T-shaped guide members 55 extending from the ends of said paddles, and hollow continuous guideways carried by the sides of the well and receiving the heads of said members to prevent the paddles from tilting.

3. The combination with a boat having a longitudinally extending well opening through its bottom; of front and rear shafts 60 extending across said well and each having a peripherally grooved wheel, an endless cable trained around said wheels, a plurality 65 of paddles extending in opposite directions from said cable, the outer ends of said paddles having ears projecting laterally therefrom, T-shaped guide members whose shanks are threaded in said ears at their free 70 ends, continuous inner and outer angle metal tracks receiving the heads of said guide members, anti-friction rollers on the ends of said heads, and similar rollers on the shanks of said guide-members.

In testimony whereof I have hereunto set my hand in the presence of two subscribing witnesses.

ELIJAH R. McCREARY.
